UNITED STATES PATENT OFFICE.

WILLIAM E. GRAVES, OF BLOOMFIELD, NEBRASKA.

PLUNGER-VALVE.

1,275,420.

Specification of Letters Patent.

Patented Aug. 13, 1918.

Application filed April 26, 1917. Serial No. 164,730.

To all whom it may concern:

Be it known that I, WILLIAM E. GRAVES, a citizen of the United States, residing at Bloomfield, in the county of Knox and State 5 of Nebraska, have invented certain new and useful Improvements in Plunger-Valves, of which the following is a specification.

This invention relates to plunger valves, and more particularly to the class of 10 plunger valves commonly employed in liquid and air pumps.

The primary object of the invention is to provide a reciprocating piston arranged to reciprocate with the action of the plunger, 15 so that the valve action will take place intermittently during the operation of the pump.

A further object of the invention is to provide a plunger valve of this character that may be minutely adjusted to regulate 20 the reciprocatory movement of the piston which forms a part of the plunger.

Another object of the invention is to provide a reciprocatory piston of this character having longitudinal open passageways 25 adapted to be intermittently opened and closed by the action of the plunger and the corresponding action of the piston during the operation of the device.

A further object of this invention is the 30 provision of a plunger valve which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, 40 wherein is illustrated the preferred form of my invention, in which:

Figure 1 is a longitudinal section through a pump casing showing my invention applied thereto in operative position.

Fig. 2 is an enlarged section on the line 2—2 of Fig. 1.

Fig. 3 is a section on the line 3—3 of Fig. 1.

Referring to the drawing, wherein is illustrated the preferred form of my invention, and in which like numerals of reference indicate corresponding parts throughout the several views, the pump casing designated at 1 may be of any desired size according to 50 the type and size of pump with which the

device is used. The plunger, designated generally at 2, is carried by the plunger rod 3, the latter being actuated by whatever power transmitting means is employed for the particular type of pump with which the 60 device is used.

The plunger rod 3 has its connecting end provided with screw threads 4, and these receive the interior screw threads of an elongated sleeve 5, the opposite end of which 65 carries a valve disk 6. This valve disk has the beveled face 7.

Mounted for sliding movement on the sleeve 5 is a piston 8, which consists of a relatively large tube 9 having its outer surface provided with screw threads 10. One end of the tube 9 has an interior passageway 11 of a diameter considerably larger than the diameter of the sleeve 5. The marginal edge of this end of the tube is rounded 75 as at 12 to provide a valve seat for the reception of the beveled surface 7 on the valve disk 6. The opposite end of the tube 9 has an annular extension 13 of relatively small diameter, so that the end of the tube forms 80 a shoulder 14, the surface of which is provided with several openings 15 spaced equidistant around the tube. These openings, as shown clearly by Fig. 2 of the drawing, extend inwardly and downwardly at an 85 angle so that they enter the passageway 11 to establish communication between the ends of the tube. By referring to Fig. 2 of the drawing it will be noted that the walls of the openings 15 merge into the 90 wall of the passageway 11 and, at the opposite end, the openings merge into the exterior surface of the annular extension 13. To accomplish this, the openings 15 extend downwardly and thereby avoid the formation of 95 any shoulders or abrupt corners at the point of juncture of the openings with the passageway 11.

The end of the sleeve 5, opposite to the end upon which the disk 6 is mounted, is provided with a plurality of screw threads for the reception of an adjusting nut 16 which may be moved to regulate the sliding movement of the piston.

The piston also includes the provision of 105 a cup packing 17 which is constructed from a suitable piece of rubber or leather of substantially cup formation. This cup packing has a central opening through which the sleeve 10 is extended and the screw threads 110

10 of the sleeve receive the nuts 18 which maintain the cup packing 17 in position on the tube.

In operation, the device will be attached 5 to the plunger rod in the above described manner, and assuming that the device is used in connection with a liquid pump, it will be obvious that an upward pull on the plunger rod will draw the piston and since 10 the openings 15 will thereby be closed, the pump will draw the liquid upwardly in the usual manner. Upon the downward movement of the plunger rod, the valve disk 6 will be forced away from the end of 15 the sleeve and the adjusting nut 16 will move into engagement with the extension 13 thus forcing the piston downwardly while, at the same time, the passageway 11 and the openings 15 will be open thus 20 permitting the liquid to pass upwardly through the sleeve. By virtue of the merging of the walls of the openings 15 with the wall of the passageway 11, any retarding of the liquid, and consequently a free 25 passage of the liquid is obtained for facilitating operation of the piston and reducing to a minimum the resistance offered by the liquid during the operation of the device. The exterior surface of the annular 30 extension 13 by virtue of its merging with the walls of the openings 15 acts to deflect the liquid when it passes through the opening to further assist in reducing the resistance offered by the liquid when the device is operated. This operation will 35 continue as long as the movement is imparted to the piston rod and the reciprocatory movement of the piston on the sleeve will

cause an intermittent opening and closing of the openings 15 to the passageway 11, so 40 that this quick changing valve action results in an efficient pump, while adapted for use for either air or liquid.

From the foregoing it will be observed that a very simple and durable plunger valve 45 has been provided, the details of which embody the preferred form. I desire it to be understood, however, that slight changes in the minor details of construction may be made without departing from the spirit of 50 the invention or the scope of the claim hereunto appended.

I claim:

A plunger of the character described comprising a sleeve having a valve disk mounted at one end, a plunger rod adjustably connected to the sleeve, a sliding tube mounted for longitudinal sliding movement on the said sleeve and provided with an adjustable cup packing on its exterior, the interior of 60 the said sleeve being provided at one end with a relatively large passageway, the said sleeve also having a plurality of openings extending from one end of the sleeve to the inner end of the said passageway, the said 65 openings being extended inwardly at an angle with respect to the longitudinal center line of the sleeve and having their interior curved walls merging with the curved wall of the said passageway. 70

In testimony whereof I affix my signature in presence of two witnesses.

WILLIAM E. GRAVES.
